No. 826,050.

PATENTED JULY 17, 1906.

A. NEUBERT.
TROLLEY POLE.
APPLICATION FILED NOV. 5, 1903.

UNITED STATES PATENT OFFICE.

AUGUSTUS NEUBERT, OF ELIZABETH, NEW JERSEY, ASSIGNOR OF ONE-HALF TO EDWARD H. RADEL, OF NEW BRUNSWICK, NEW JERSEY.

TROLLEY-POLE.

No. 826,050.

Specification of Letters Patent.

Patented July 17, 1906.

Application filed November 5, 1903. Serial No. 179,986.

To all whom it may concern:

Be it known that I, AUGUSTUS NEUBERT, a citizen of the United States, residing at Elizabeth, in the county of Union and State 5 of New Jersey, have invented certain new and useful Improvements in Trolley-Poles, of which the following is a specification, reference being had therein to the accompanying drawings.

10 My invention relates to improvements in trolley-poles for electric-railway cars; and it consists in the construction and arrangement of devices hereinafter described and claimed.

15 My improved trolley-pole is especially adapted for use on trolley-lines equipped with the improved cross-town arches described and claimed in my copending application for Letters Patent of the United States, Serial No. 184,642, filed December 20 10, 1903, and equipped also with my improved switch-arches described and claimed in my copending application for Letters Patent of the United States, Serial No. 181,734, filed November 18, 1903.

25 In the accompanying drawings, Figure 1 is a perspective view of a trolley-pole and trolley-wheel embodying my improvements. Fig. 2 is an elevation of the same in connection with a cross-town arch, the latter being 30 indicated in cross-section. Fig. 3 is a detail perspective view showing a modified form of my improved trolley-pole.

The trolley-pole 1 here shown is hollow and is provided with a fork 2, the arms 3 of which 35 are appropriately spaced apart and lie in parallel vertical planes. The trolley-wheel 4 is mounted for revolution between these arms, and its lateral sides are nearly in contact with the inner sides of said arms, as shown. This 40 prevents the trolley-wire *a* from getting between the trolley-wheel and either of the fork-arms. The latter are of such length as to have extended portions 5, that project beyond the periphery of the trolley-wheel, and 45 at the outer ends of the said extensions the fork-arms are provided with outwardly-diverging prongs 6, which extend in front and rear of the trolley-wheels and also above it. In the form of my invention shown in Fig. 1, 50 these prongs are in the same planes as the fork-arms. In the form shown in Fig. 3 the prongs of the respective fork-arms diverge laterally. This enables the trolley-wheel to be readily applied to the trolley-wire, as the

laterally-diverging prongs serve as guides to 55 coact with the trolley-wire and direct the trolley-wheel thereto. The prongs of the trolley-fork in both of the forms of my invention here shown serve to pass on the inner sides of the side walls of the arches at the 60 crossings and switches of the trolley-wires and by coaction with said side walls of the arches prevent the trolley-wheel from casually disengaging the trolley-wire while passing through and under the arches. The side 65 walls of the arches are sufficiently spaced from the trolley-wires to afford clearance for the prongs of the trolley-fork. This is indicated in Fig. 2, *b* designating an arch, and *c* the side walls thereof.

70 The trolley-wheel 4 is provided with the usual circumferential peripheral groove to receive the trolley-wire and is of such diameter as when passing the opening at the crossing of the trolley-wires to maintain electric contact with the trolley-wire on which it is operating.

75 By the provision of the forwardly and rearwardly projecting prongs of the trolley-fork the trolley-wheel is prevented from casually becoming disengaged from the trolley-wire either when the car is going forward or backing; but the trolley-pole can be lowered as usual when it is desired to disengage the 80 trolley-wheel from the trolley-wire.

85 When the trolley-wheel passes under the upper trolley-wire *x* in a cross-town arch and is opposite the opening in the lower trolley-wire *a*, as shown in Fig. 2, the prongs 6 by 90 reason of the fact that they extend in front and rear of the trolley-wheel, as hereinbefore described, are in position to engage the walls of that arm of the arch through which the lower trolley-wire extends should the trolley-wheel move laterally, so that the said prongs 95 and the walls of the cross-town arch coact to prevent the trolley-wheel from moving laterally and out of engagement with the lower trolley-wire when opposite the opening therein and under the upper trolley-wire.

100 It will be observed by reference to Fig. 2 that the width of the opening in the lower wire under the upper wire is very much less than the diameter of the trolley-wheel, so that the wheel when running under the lower 105 wire and passing under the upper wire prevents the fork from moving upwardly so far as to come in contact with the upper wire.

Having thus described my invention, I claim an ddesire to secure by Letters Patent.

The herein-described arrangement of crossed trolley-wires at different elevations, 5 the upper wire being continuous and the lower wire having an opening directly below the upper wire, in combination with a trolley-pole having a fork and a trolley-wheel, the said trolley-wheel engaging the lower trolley- 10 wire and being of a diameter exceeding the width of the space or opening in the lower

wire to prevent the fork from moving upwardly so far as to come in contact with the upper wire when the wheel is passing under the upper wire, substantially as described. 15

In testimony whereof I affix my signature in the presence of two witnesses.

AUGUSTUS NEUBERT.

Witnesses:

C. ADDISON SWIFT,
ROBERT L. EATON.
